UNITED STATES PATENT OFFICE.

JOSEPH THOMPSON PARKER, OF WASHINGTON, DISTRICT OF COLUMBIA.

STABILIZER FOR AEROPLANES.

1,149,680.

Specification of Letters Patent. Patented Aug. 10, 1915.

Application filed January 15, 1915. Serial No. 2,427.

To all whom it may concern:

Be it known that I, JOSEPH THOMPSON PARKER, a citizen of the United States, residing at Washington, District of Columbia, 5 have invented certain new and useful Improvements in Stabilizers for Aeroplanes, of which the following is a specification.

My invention relates to stabilizers for aeroplanes.

10 The object of the invention is to provide means whereby the stability of aeroplanes may be automatically maintained by the start of the sustaining planes to assume an angle by the wind and by said means the 15 machine will maintain a horizontal position at all times. Further objects and advantages will be more fully described herein and specifically pointed out in the annexed claims recourse being had to the accompanying 20 drawing forming a part of this specification in which:

Figure 1 is a front perspective view of the sustaining planes in normal position with my device located between them. Fig. 2 is 25 a side view, and Fig. 3 is a fragmentary front view of a portion of the lower sustaining plane and is an enlargement of that shown in Fig. 1.

In the drawing, like reference numerals 30 indicate similar parts in all the several views.

1 represents the upper and 2 the lower sustaining planes of an aeroplane arranged one above the other, as shown.

35 3 are the supports or connectors for the planes, and 4 is the lower frame work or landing portion of the apparatus.

5 and 6 are the two rockable planes or stabilizers placed about midway between the 40 planes 1 and 2 and at the ends thereof leaving an unoccupied space in the center, as shown in Fig. 1. The planes 5 and 6 are provided with short axles 7, at their transverse centers which are mounted in the 45 standards or supports 8 and are, consequently, adapted for oscillation therebetween.

9 is a counterpoise, center or pendulum placed below the lower plane 2 and is provided with a tapering or bevel top portion 10, Fig. 3, which permits the planes 1 and 2 to rock thereon and to assume an angle according to the inclination or "careen" thereof under the influence of the wind. The 55 lower plane or its frame work is rockably

secured to the part 9 by means of the hinge joint 11 and its pin 12, Fig. 3.

The stabilizing planes 5 and 6 are automatically made to assume angles for maintaining stability by the center remaining 60 perpendicular, while the sustaining planes depart from the horizontal, thus pulling and slackening ropes or wires which will now be described.

Assuming that Fig. 1 is a front view, a 65 wire or cable 13 extends from the right hand front corner of the controller, center or pendulum 9, through a pulley, thence vertically to the front edge of the left hand stabilizing plane 6. On the opposite side, the wire 14 70 operates the plane 5 at its front edge in the same manner as the wire or cable 13.

15 is a wire or cable from the rear right hand corner of the pendulum 9, to a pulley, thence horizontally along the rear of the 75 lower plane 2, thence again vertically to the rear edge of the stabilizing plane 5.

The wire 16 is similar but reverses to the plane 6.

17 is a wire secured to the pendulum at 80 the same point as the wire 13, goes to a pulley, and thence vertically to the upper front edge of the top sustaining plane 1, thence along said edge then vertically to the front of the stabilizer 5 near the end of the 85 wire 14.

The wire 18 starts from the left hand front side of the pendulum or center 9 thence to the lower front edge of the plane 2, thence vertically and then horizontally along 90 the front edge of plane 1 and then drops straight downward to near the front center portion of the stabilizing plane 6.

As will be seen, when a wire pulls to tighten, the opposite wire slackens. When 95 the right hand side of the biplane is depressed then the wires will act and cause the plane 6 to rise which will cause the wind to maintain the equipoise or balance of the machine.

100 It will be observed that the pendulum is elongated in a fore and aft direction, whereby the rear cables may be carried directly up to the rear ends of the stabilizing planes and the front cables may be carried directly 105 up to the front edges of the stabilizing planes, thereby avoiding the necessity of pulling the cables diagonally of the machine. By thus arranging the cables, a direct pull 110 on the stabilizing planes is provided for,

thereby insuring promptness of action of the stabilizing planes and also the highest degree of stability. It will also be seen that I connect to the rear edge of the stabilizing planes at least one cable for pulling as well as holding down the rear edges of the planes and that I connect to the front edge of each stabilizing plane two cables for pulling and holding them in opposition to each other.

10 This arrangement of cables is advantageous in that it provides ample cable strength for holding the stabilizing planes when under great strain.

I claim:—

15 The combination with an aeroplane, of a pendulum elongated in a fore and aft direction, a pair of stabilizing planes pivoted at points between their front and rear edges, a cable connecting the rear edge of each plane

to the rear end of the pendulum, and a pair 20 of cables connecting the forward edge of each stabilizing plane to the opposite sides of the pendulum at the forward edge thereof, one of these latter cables extending from the front edge of the plane directly downwardly to the pendulum and the other cable 25 extending upwardly from the plane, and thence around to the opposite side of the pendulum, suitable pulleys being provided for all of said cables.

In testimony whereof I have hereunto affixed my signature in the presence of two witnesses.

JOSEPH THOMPSON PARKER.
